AIR DISTRIBUTING DEVICE

Charles Demuth, Mineola, N. Y., assignor to
 Charles Demuth & Sons, Inc., Mineola, N. Y., a
 corporation of New York

Application February 28, 1952, Serial No. 274,020

7 Claims. (Cl. 98—40)

1

This invention relates to air distributing devices and more particularly to distributors adapted to take off air from a running air duct common to a plurality of distributors.

In distributors which are connected to individual ducts or ducts having individual branch outlets for respective distributors it is practicable to equalize the flow of air to be distributed. However, where running ducts are employed having substantial length, and especially where the cross-sectional area is substantially uniform throughout a given length where a plurality of take-offs are desired, it is necessary to provide means for adequately adjusting the amount of air at respective take-off points. In the running ducts of the character referred to the air velocity ranges from a minimum of about 900 feet per minute to a maximum of about 1,800 feet per minute, depending largely upon the height of the ceiling. For example, for a ceiling having a height less than 15 feet it is accepted practice to have an air velocity of about 1,000 to 1,200 feet per minute and for ceilings having a height of 15 to 20 feet an air velocity of about 1,500 to 1,800 feet per minute. With such air velocities it has been found difficult to deflect the air downwardly at the respective distributor outlets with a substantially uniform distribution throughout the cross-section of the distributor neck. It is likewise important to reduce to a minimum interference to the flow of air. It has been proposed to use flat dampers in the running duct at the respective distributor neck openings and by adjusting these dampers to equalize the distribution of air. However, such dampers tend to concentrate the air toward one side of the distributor neck, which makes it difficult—if not impossible—to reduce substantially uniform air flow throughout the cross-sectional area of the distributor neck; and, additionally, these plates present substantial resistance to the air flow in the running duct.

An object of this invention is to provide a device adapted for attachment to running air ducts so constructed as to facilitate attachment to the air duct at desired points.

Another object of the invention is to provide a device of the character described which deflects air from the running duct into the distributor neck in a substantially uniform cross-sectional flow.

Another object of the invention is to provide a device of the character described which offers a minimum of interference to the flow of air through the running duct.

2

Further objects and advantages of the invention will more fully appear from the following description taken in connection with the accompanying drawings which show, by way of example, the present preferred embodiment of the invention.

The invention consists of the novel features and arrangement of parts embodied, by way of example, in the structure hereinafter described 10 as illustrating a present preferred form of the invention, and the invention will be more particularly pointed out in the appended claims.

Referring more particularly to the drawings: Fig. 1 is a perspective view, partly in section, 15 showing a distributing unit secured to a running air duct;

Fig. 2 is a cross-sectional view taken substantially along the line 2—2 of Fig. 3, with certain portions broken away;

Fig. 3 is a longitudinal cross-sectional view taken substantially along the line 3—3 of Fig. 1; Fig. 4 is a fragmentary sectional view showing further details of certain of the parts shown in Figs. 1 and 3;

Figs. 5 and 6 are cross-sectional views taken respectively at lines 5—5 and 6—6 of Fig. 3; and

Fig. 7 is a side elevational view, partly in section, and Fig. 8 is a plan view illustrating a modification of the device shown in Figs. 1-6, inclusive.

Referring more particularly to Fig. 1: the running air duct is designated as 1 and the direction of air flow is indicated by arrows. The distributing device is designated in general as 2 and is provided with a neck portion in the form of a cylindrical take-off pipe which, to facilitate production and assembly, preferably comprises an upper section 3 and a lower section 4 suitably secured together by screws, such as 5. The upper section is provided with a flange 6 adapted to be secured as by screws 7 to the lower side of the duct 1 surrounding an outlet opening in the duct in register with the interior of the pipe 3. A hood designated in general as 8 is provided with a sleeve 8a slidably engaging the exterior of the lower pipe section 4, an outer horizontal skirt portion 8b and an intermediate conical section 8c. Secured within the interior of the hood sleeve 8a, adjacent the lower end thereof, are a plurality of curved deflector vanes, such as 9, which extend downwardly below the hood 8 and carry fixed to their lower edges a conical deflector 10 closed at its upper end. Secured in spaced relation beneath the cone 10 is a conical deflector 11 provided with an open upper end 12. The ar-

angement of the conical members 10 and 11 and the curved vanes 9 being in general quite similar to that shown in my Patent No. 2,367,104, except that in the present invention the vanes and conical members are fixed with respect to the hood member 8 in a manner now to be described below. The structure thus far described provides the distributor neck or take-off pipe having an outlet distributor end; and I will now describe the means for adjusting the volume of air taken off from the running duct.

Within the lower pipe section 4 is secured a diametrically extending journal strut 13 and within the pipe section 3, adjacent the lower end thereof, there is secured a corresponding journal strut 14. An externally threaded hollow tubular member 15 is freely rotatably journaled in the journal strut 13 and is fixed against axial movement by means of a pair of nuts 16 (Fig. 3), which are in threaded engagement with the tube 15 and are secured respectively against the upper and lower faces of the journal strut 13. The lower end of the threaded tube 15 extends freely through an opening in the upper end of the cone 10 and a nut 17 is in threaded engagement with the lower end of the tube 15 and serves as a means of supporting the hood 8 and the vanes 9 and cones 10 and 11 secured thereto. Within the bore of tube 15 there is freely rotatably disposed the lower end of a shaft 18 which is fixed against axial movement by a slotted head 19 carried on its lower end and by a retaining ring or boss 20 engaging the upper end of the tube 15. The upper end of the shaft 18 is non-circular (for example, square) and is telescopically disposed within a tubular shaft extension 21 with which it is rotatably drivingly connected by a corresponding square opening provided within the tubular shaft extension 21 (Fig. 6). The tubular shaft 21 is freely rotatably journaled adjacent its lower end in the journal strut 14 and is fixed against axial movement with respect thereto by means of a pair of nuts 22b secured to the shaft 21 above and below the strut 14 (Figs. 1 and 3) so as to permit rotation of the shaft 21 by means of the shaft 18 while holding the shaft 21 against axial movement. The tubular shaft 21 is exteriorly threaded and its upper end is in threaded engagement with a scoop member 22 so that upon rotation of the members 18 and 21 the scoop member 22 may be adjusted to the desired position between the limits indicated by the lower dotted lines and the upper solid lines. The upper limit of the scoop 22 is limited by a stop, such as a nut 21a, which is secured to the upper end of the tubular shaft 21. The scoop 22 is restrained from angular movement, as by means of an arm 24 rigidly secured thereto and extending downwardly within the upper pipe section 3 and slidably disposed within a clip 25 which is rigidly secured to the interior of the pipe section 3.

The scoop 22 is of concave form of generally conical shape (see also Fig. 1) having a closed top and downwardly and outwardly flaring walls. The scoop is set on the tubular shaft member 21 at a positive angle of incidence, such as θ , to the top of the pipe 3 and the axis A—A of the cone is preferably asymmetrical to the axis of the adjusting shaft 21.

The scoop arrangement has been found to produce substantially perfect uniform distribution throughout the cross-section of the distributor neck. However, at certain velocities and settings it has been found desirable to utilize an inwardly

and downwardly inclined segmental baffle 26 secured interiorly of the pipe section 3, adjacent the lower end thereof, and disposed beneath the rear end of the scoop 22.

From the foregoing it will be apparent that the device is so designed that it may be made with facility and economy, both as to fabrication of its parts and as to assembly. Furthermore, it is adapted to be readily and quickly installed as a completely assembled unit entirely from the outside of the running duct 1, simply by inserting the screws 5 through the flange 6 and in threaded engagement with the bottom wall of the running duct 1.

By means of the nuts 22 and 21a the upper limit of the scoop 22 may be readily set at the predetermined height before the device is fastened into place but while on the job and without any necessity for alterations. Likewise, by means of the nuts 16 and 17 the output end deflector head may be readily removed and replaced to permit easy access to the interior of the pipe section 4, such as for adjustment of the nuts 22.

It will be understood that the scoop 22 is of such diameter as to permit its peripheral margin portion to freely slide interiorly of the pipe section 3.

MODIFICATION

In certain installations where it is desired to reduce the distance which the device extends below the duct, as where the running duct is relatively low (e. g. is disposed beneath a beam) a modified form of the invention has been found useful.

In Figs. 7 and 8 I have shown such a modification, in which the running duct is designated as 1' and the upper section of the take-off pipe as 3'. In this case an annular flange 6' is formed a short distance (say about $3\frac{1}{4}''$ — $1\frac{1}{2}''$) from the lower end, to provide for securing the lower section 4 (Figs. 1 and 3) thereto, as shown in dotted lines; it being understood that in this modified embodiment the lower section and all parts carried thereby are identical with the embodiment shown and described with reference to Figs. 1-6, inclusive. The upper section 3' extends upwardly for its maximum height throughout only about 180° of its diameter corresponding to the rear section 3'a and is substantially reduced in height for the forward half of its diameter designated 3'b, which is the effective intake end.

A threaded tubular sleeve 21' is freely rotatably journaled in a journal strut 14' and is restrained against axial movement therein and threadingly engages a scoop member 22', constructed and arranged in the manner previously described with respect to Figs. 1-6, inclusive, except for the specific differences now to be described.

In the modified structure the upper end of the shaft 21' passes freely through a support strap 27 supported on downwardly extending legs secured respectively to the rear and front walls of pipe sections 3'a and 3'b respectively. The scoop cone 22' is restrained against angular movement by means of a bifurcated plate 24' secured to the scoop 22' and straddling the front leg of the strap 27. A segmental baffle 26' is shown rigidly fixed interiorly of the cone scoop 22' instead of being supported on the interior of the pipe section, as in Figs. 1 and 3.

Except for the differences above described relative to the upper section, the modified device is the same as the embodiment described

with reference to Figs. 1-6, inclusive, and functions in a substantially identical manner.

Having thus described my invention with particularity with reference to a presently preferred form of the same, and a modification thereof, it will be obvious to those skilled in the art after understanding the invention, that various other changes and modifications may be made therein without departing from the scope of the invention, and it is my intention to cover in the appended claims such changes as come within the scope of the invention.

What I claim is:

1. In an air distributing device, the combination of a take-off pipe for use as an outlet to an air duct, a concave scoop for directing air into said pipe from said duct, said scoop having a lower peripheral marginal portion whose external diameter is smaller than the internal diameter of said pipe and said scoop being movable axially of said pipe to slide interiorly of the intake end of said pipe to substantially restrict the inlet opening thereof, said scoop extending from said peripheral marginal portion upwardly and inwardly in gradually decreasing diameter to a closed central zone, means for holding said scoop with its peripheral margin disposed at a positive angle of incidence relative to the intake end of said pipe at all times and in register therewith, and means for adjusting said scoop toward and away from the intake end of said pipe to vary the inlet opening thereof while retaining a said positive angle of incidence of said scoop.

2. In an air distributing device, the combination of a take-off pipe for use as an outlet to an air duct, a concave scoop of generally conical form for directing air into said pipe from said duct, and a shaft angularly adjustable and axially disposed within said pipe and having an upper end on which said scoop is adjustably mounted, said scoop having a lower peripheral margin portion adapted to slide interiorly of the intake end of said pipe to substantially restrict the same, means for holding said scoop asymmetrically disposed relative to the axis of said pipe with its peripheral margin disposed at a positive angle of incidence to the intake end of said pipe.

3. In an air distributing device, the combination of a take-off pipe for attachment to a running air duct, an adjusting rod rotatably journaled within said take-off pipe and restrained against movement in an axial direction, the lower end of said rod being provided with an engageable end extending to adjacent the lower end of said pipe and the upper end of said rod being provided with external screw threads and extending beyond the inlet end of said pipe, a concave scoop of generally conical shape supported in threaded engagement with the upper end of said adjusting rod for axial movement thereon when said rod is rotated, said scoop flaring downwardly and outwardly with its lower perimeter disposed at a positive angle of incidence to the top of said pipe and being of a diameter permitting the downwardly extending portion thereof to be retracted within said pipe, and means for restraining said scoop against angular movement.

4. In an air distributing device, the combination of a take-off pipe for attachment to a running air duct, a deflector cone providing a downwardly and outwardly flaring wall fixed in axially spaced relation to and concentric with the outlet end of said pipe, an adjusting rod rotatably

journaled within said take-off pipe and restrained against movement in an axial direction, the lower end of said rod being provided with an engageable end extending through said 5 deflector cone and the upper end of said rod being provided with external screw threads and extending beyond the inlet end of said pipe, a concave scoop of generally conical shape supported in threaded engagement with the upper 10 end of said adjusting rod for axial movement thereon when said rod is rotated, said scoop flaring downwardly and outwardly with its lower perimeter disposed at a positive angle of incidence to the top of said pipe and being of a diameter permitting the downwardly extending portion thereof to be retracted within said pipe, and means for restraining said scoop against angular movement.

5. In an air distributing device, the combination 20 of a take-off pipe for attachment to a running air duct, said pipe comprising an upper section and a lower section, an adjusting rod comprising an upper section and a lower section, a first journal strut disposed within and secured 25 to said upper pipe section, said upper rod section being rotatably journaled in said first journal strut and having its upper end extending outwardly beyond the upper end of said upper pipe section, a second journal strut disposed within 30 and secured to said lower pipe section, said lower rod section being rotatably journaled in said second strut in telescopic relationship and rotatable driving engagement with said upper rod section, the lower end of said lower rod section being 35 provided with an engageable portion disposed adjacent the lower end of said lower pipe section, a concave scoop of generally conical shape supported on the outwardly extending end of upper rod section for axial movement thereby when 40 said rod is rotated, said scoop flaring downwardly and outwardly with its lower perimeter disposed at a positive angle of incidence to the top of said pipe and being of a diameter permitting the downwardly extending portion thereof to be retracted within said pipe, and means for restraining 45 said scoop against angular movement.

6. In an air distributing device, the combination 50 of a take-off pipe for attachment to a running air duct, said pipe comprising an upper section and a lower section, a deflector cone providing a downwardly and outwardly flaring wall fixed in axially spaced relation to and concentric with the outlet end of the lower section of said pipe, an adjusting rod comprising an upper section 55 and a lower section disposed axially of said pipe, said sections being telescopically arranged to provide for varying rod lengths and being in rotatable driving engagement one with the other, said upper rod section being rotatably journaled 60 within the upper section of said take-off pipe and restrained against movement in an axial direction, the upper end of said upper rod section being provided with external screw threads and extending beyond the inlet end of said pipe, said 65 lower rod section being rotatably journaled within the lower section of said pipe and provided with an engageable end extending through said deflector cone, a concave scoop of generally conical shape supported in threaded engagement with the upper end of said adjusting rod for axial movement 70 thereon when said rod is rotated, said scoop flaring downwardly and outwardly with its lower perimeter disposed at a positive angle of incidence to the top of said pipe and being of a diameter permitting the downwardly extending 75

portion thereof to be retracted within said pipe, and means for restraining said scoop against angular movement.

7. In an air distributing device, the combination of a take-off pipe for attachment to a running air duct, said pipe comprising an upper section and a lower section, an adjusting rod comprising an upper section and a lower section, a first journal strut disposed within and secured to said upper pipe section, said upper rod section being rotatably journaled in said first journal strut and having its upper end extending outwardly beyond the upper end of said upper pipe section, a second journal strut disposed within and secured to said lower pipe section, said lower rod section being rotatably journaled in said second strut in telescopic relationship and rotatable driving engagement with said upper rod section, the lower end of said lower rod section being provided with an engageable portion disposed adjacent the lower end of said lower pipe section, a concave scoop of generally conical shape supported on the outwardly extending end of upper rod section for axial movement thereby when said rod is rotated, said scoop flaring downwardly and outwardly with its lower perimeter disposed at a positive angle of incidence to the

10
15

5 top of said pipe and being of a diameter permitting the downwardly extending portion thereof to be retracted within said pipe, means for restraining said scoop against angular movement, and an inwardly and downwardly inclined segmental baffle secured interiorly of said pipe adjacent the lower end of its upper section and disposed beneath the rear edge of said scoop.
